Attorney

UNITED STATES PATENT OFFICE.

GUY C. WALLIS, OF WAYCROSS, GEORGIA.

VALVE AND CATCH POCKET.

Application filed June 6, 1924. Serial No. 718,353.

To all whom it may concern:

Be it known that I, GUY C. WALLIS, a citizen of the United States, residing at Waycross, in the county of Ware and State 5 of Georgia, have invented certain new and useful Improvements in a Valve and Catch Pocket, of which the following is a specification.

This invention relates to a valve and catch 10 pocket structure and it consists in the novel features hereinafter described and claimed.

An object of the invention is to provide a structure of the character stated adapted to be used for feeding exhaust oil and water 15 from the steam end of an air pump to the air end thereof by suction created at the air end of the pump.

In the accompanying drawing:—

Figure 1 is a side view of a pump with the 20 valve and pocket connected thereto.

Figure 2 is a transverse sectional view of the pocket.

Figure 3 is a horizontal sectional view of the pocket.

25 Figure 4 is a vertical sectional view of the valve.

Figure 5 is a transverse sectional view of the valve.

As illustrated in the accompanying drawing, the pump comprises a steam cylinder 1 and an air cylinder 2, the steam pipe 3 connects with one end of the cylinder 1 and an exhaust pipe 4 also connects with said cylinder 1. A pocket 5 is connected in the 30 pipe 4 and a pipe 6 connects the pocket 5 with the cylinder 2. The pocket 5 is provided with a longitudinally disposed partition wall 7 located in the lower portion thereof and which divides the lower portion 35 of the pocket into chambers 8. A boss 9 is located at one side of the partition 7 and connects with the pipe 6 as shown in Figure 1. A plurality of bosses 10 is located at the opposite side of the partition 7 and a plurality of pipes may be connected with the bosses 10 when it is desired to connect the pocket with a compound pump or a series 45 of pumps. A valve structure 11 is connected in the pipe 6 and said structure includes a 50 casing 12 having a partition 13 located therein, the said partition being provided

with a central opening 14. A nipple 15 is screwed in the lower end of the casing 12 and a ball 16 is housed within the casing 12 and rests upon the upper end of the nipple 15 and normally closes the main passageway 55 through the nipple. Ducts 17 lead in from the upper end of the nipple 15 and communicate at their lower ends with the passageway 18 through the nipple 15 at points 60 below the ball 16.

During the operation of the pump the water and oil which is exhausted from the cylinder 1 is connected in the pocket 5 and passes down through the pipe 6 and enters 65 the cylinder 2 when suction is created therein. The oil and water passes through the opening 14 in the partition 13 of the casing 12 and flows down over the ball 16 and passes through the ducts 17 into the 70 passageway 18 in the nipple 15. When back pressure is created in the pipe 6, the ball 16 is lifted by said pressure and closes the opening 14 in the partition 13 thereby interrupting the flow of oil and water through the 75 casing 12.

Thus it will be seen that simple and efficient means are provided for passing the exhaust water and oil from a steam cylinder to an air cylinder for the purpose of lubricating the operating parts in the air cylinder. 80

Having thus described the invention, what I claim is:—

1. In combination with a pair of cylinders, an exhaust pipe connected with one of the cylinders, a pocket connected in the exhaust pipe, a pipe connecting the pocket with the other cylinder, a check valve connected in the last mentioned pipe, the said check valve having by-pass ducts communicating with the passageway therethrough. 85

2. A valve comprising a casing having a partition provided with a central opening, a nipple screwed in the casing and provided with a passageway, a ball housed in the casing below the partition and normally closing the passageway through the nipple, the nipple being provided at its inner end with by-pass ducts which communicate with the passageway at points below the ball. 95

In testimony whereof I affix my signature.
GUY C. WALLIS.
